**METHOD AND MEANS OF
SUPERCALENDERING**

Willard G. Engelhau, Rhinelander, Wis., assignor to St. Regis Paper Company, a corporation of Wisconsin

Application January 23, 1958, Serial No. 710,695

9 Claims. (Cl. 100—41)

This invention relates generally to supercalendering, and more specifically to an improved method and means of supercalendering paper.

Although the principles of the present invention may be included in various supercalenders, a particularly useful application is made in supercalenders which are used to supercalender more than one width of paper.

A brief review of the art of supercalendering will be helpful in the understanding of this invention. Supercalendering per se is well known to the paper industry and is used with suitable variations in the processing of many kinds of paper to give each kind of paper the desired smoothness, gloss, density, or transparency and combinations of these characteristics. The device used for this purpose is a supercalender which usually comprises a vertical stack of rolls or rollers in which some of the rolls are hard, such as being made of steel, and some of the rolls are relatively soft, such as being made of compressed paper or other fiber. The number and arrangement of rolls is varied to suit the requirements of the specific grade and the hard and soft rolls are generally alternated, though several hard or soft rolls may be run together.

Usually only the bottom roll of the stack is driven, although other rolls may be driven. The paper to be treated is unwound and is threaded through the stack from the top to the bottom passing through some or all of the nips between rolls, and if desired may be led away from the rolls between nips over fly rolls principally to provide for and to control the drying of the paper which may be at an entering moisture content ranging from about four to about thirty percent.

As the paper passes downwardly through the stack, it is subjected to pressing at increasing pressure at each nip due to the weight of the rolls. Extra loading may be applied through the journals of the top roll. Thus pressures at the bottom nip may range from less than one-thousand pounds to more than four-thousand pounds per linear inch. The stack may be operated at speeds ranging from about four hundred to more than two thousand feet per minute. Shear forces are exerted on the paper by the deformation of the soft rolls which occurs at the nip, and the nature of this deformation is determined largely by pressure, speed, and the material from which the soft rolls are made. The manner in which the method of operating a supercalender stack may be changed to accomplish the different results with specific grades of paper is well known in the industry.

One principal difficulty in operating a supercalender is the one of avoiding uneven wear and damage to the soft rolls of the stack. The paper web usually does not extend across the complete width of the soft rolls and maximum wear occurs on the area engaged by the paper web. If a constant width of paper is run in the same position, it becomes necessary at intervals to sand or otherwise dress the exposed ends of the soft rolls outside of the area engaged by the paper.

If successive rolls of paper being calendered are of

2

decreasing width, a series of wear ridges will develop on the rollers which corresponds to the position of the edges of the paper. Similarly, if successive paper rolls increase in width, the edges of the first part of at least the first roll of each increased width will be calendered harder than the balance of the width at these edges are running between portions of the roller which are less worn than the portions of the roller in the central portion of the paper web.

10 If several narrow rolls of paper are supercalendered and then it is desired to supercalender several wider rolls of paper on the same stack, the soft supercalender rolls must be dressed or refinished prior to running the wider paper rolls, because if this not be done, the position of the edges of the narrower roll of paper will show in a number of successive rolls of paper of a wider width.

I have found that the ridging of the supercalender rolls and hence the need for dressing them can be eliminated by continually moving back and forth, or oscillating, a web of paper being calendered which has a width less than the full width of the soft rolls, so that as the web moves from one axial limit of the roller to the other, the web comes in contact with all or a large portion of the useful surface of the soft rolls or rollers.

20 25 Accordingly, it is a principal object of this invention to provide for more uniform wear of the soft rolls of rollers or stacks, particularly as the width of paper changes either because of variable shrinkage in the paper, or because of deliberate changes in the widths being calendered.

30 Another object of the present invention is to obtain more uniform wear results with less frequent dressing of soft rolls, and to reduce or eliminate differences in finish or other characteristics of the paper, such differences being produced by the supercalendering, and which would be objectionable and which results from uneven wear of the supercalender rolls.

35 Yet another object of the present invention is to minimize roll defects commonly known as ridges or corrugations which result from damaged or worn areas in the soft or hard rolls, as the effect of these usually minute imperfections is multiplied in the finished roll of paper as the diameter thereof increases.

40 45 Many other advantages, features, and additional objects of the present invention will become manifest to those versed in the art upon making reference to the detailed description and the accompanying sheets of drawings in which a preferred structural embodiment incorporating the principles of the present invention is shown by way of illustrative example.

50 On the drawings:

Figure 1 is a diagrammatic end view of a supercalendering machine;

55 Figure 2 is a diagrammatic view taken along line II—II of Figure 1;

Figure 3 is a side elevational view, partly diagrammatic, of an unwinding mechanism for a paper roll;

Figure 4 is a front view of a rewinding mechanism, and is also partly diagrammatic; and

60 Figure 5 is a fragmentary schematic view of a pair of adjacent supercalender rolls, the view being greatly enlarged in the vertical direction.

As shown on the drawings:

65 The principles of this invention are particularly useful when embodied in a supercalender stack such as illustrated in Figures 1 and 2, generally indicated by the numeral 10. The stack includes a series of soft or paper filled rolls 11 and a series of hard rolls 12 such as of steel. The steel roll or rollers 12 may be steam-heated if desired, and the uppermost steel roll may be provided with means 13 for applying additional loading through the bearings to the journals of the roll. A series of fly rolls

14 may be provided to lead the paper away from one pair of rolls and back into the stack where an additional nip or squeeze is present. One or more carrying rolls 15 may also be provided as desired.

A roll of uncalendered paper 20 is supported by an unwinding mechanism 21, and a roll of calendered paper 22 is shown as supported by a rewind mechanism 23.

Referring to Figure 2, it will be noted that the soft rolls 11 have been shown as being somewhat shorter in length than the steel rolls 12, and that the paper web 24 is at one limit of the useful width of the stack, the width of the paper rolls and paper web being somewhat less than the width of the soft stack rolls 11.

Figures 1 and 2 are obviously schematic, and the various rolls are maintained in alignment in a suitable frame having ways for the bearings of each journal, while the unwind and rewind mechanisms include shafts supported on suitable brackets or frames. These details have been omitted since they are well known in the art, since they do not form a part of the instant invention, and since a clearer result is obtained by their omission.

Referring now to Figure 3, there is shown a front view of the unwind mechanism generally indicated by the numeral 21. The mechanism 21 includes a horizontal shaft 30 which corotatably supports a core 31 for the roll of paper to be unwound. The shaft 30 is rotatably supported by a pair of split bearings 32 and 33. The bearing 32 also slidably supports the shaft 30 with respect to a portion of the frame 45 of the supercalender. The bearing 33 is supported by a slide assembly 34 which includes a stub shaft 35 bearingly mounted thereon. The stub shaft 35 has a helper drive pulley and friction drum assembly 36 at one end thereof, and a slide coupling 37 is provided at the other end thereof for rotatably joining the shafts 30 and 35 together, for corotation. The slide assembly 34 is laterally movable on a slide or ways 40 by means of the action of a hydraulic actuator 41 which is operatively connected intermediate the slide assembly 34 and the slide 40. A portion 42 of the slide assembly 34 is arranged to alternatively engage means such as valves or limit switches 43 which are operatively connected to valves (not shown) which control a fluid pressure medium directed to the hydraulic actuator 41. The fluid system employed to reciprocate the slide assembly 34 may be any of the well-known systems and does not form a part of the instant invention, and therefore it need not be shown herein in greater detail.

The core 31 is secured to the shaft 30 by any convenient means which prevents relative axial or angular movement therebetween. The shaft 30 may be held in position in relation to the slide assembly 34 by a collar 46 affixed to the end of the shaft 30, which bears against the bearing 33, and the adjacent end of the stub shaft 35. If desired, a second collar 46a may also be employed. The bearing 33 is of split construction for opening for easy removal of the shaft 30 therefrom, and the bearing 32 is of similar construction.

Referring now to Figure 4, there is shown a front view of the rewind mechanism generally indicated by the numeral 23. The rewind mechanism 23 includes a shaft 50 which axially slidably and corotatably supports a core 51 for supporting the rewind roll 22, their mutual surfaces, by way of example being non-circular or splined. The rewind mechanism includes a right and left-hand threaded screw 52 which threadably engages with a pair of arms 53 and 54. The core 51 is disposed intermediate the distal ends of the arms 53 and 54 at which ends a plurality of rollers 55 may be provided.

By means of a hand wheel 56 corotatably carried on the end of the shaft 52, the arms 53 and 54 may be moved away from and toward each other so that cores of various lengths may be carried therebetween.

The shaft 50 is rotatably supported on a frame 71, 71 by a pair of split bearings 58, 58 so that the reciprocation of the arms 53 and 54 will cause the core 51 to be re-

ciprocated axially relative to the shaft 50. The shaft 50 is provided with at least two oppositely directed collars 59a or shoulders which preclude axial shaft movement, one of which is removable. The shaft 50 may be rotated by means of a helper drive pulley and friction drum assembly 57 carried on a stub shaft 35a which corotatably is removably joined to the shaft 50 by a slide coupling 37a. The shaft 50 and core 51 may thus be removed from the mechanism, the connection with the arms 53, 54 being releasable. The shaft 35a is bearingly supported by stationary means equivalent to that shown for the stub shaft 35 in Figure 3.

The arms 53 and 54 are supported by rollers 60 which engage a track or ways 61, and which are movable therealong. A hydraulic actuator 62 is operatively connected to the shaft 52 or to the arm 54 for reciprocating the core 51 in a direction parallel to its axis.

The rewind mechanism 23 is provided with a means for aligning the edge of the calendered paper with respect to a reference point which is movable with the core of the rewind mechanism 23. Referring to Figure 1, there is shown a source of light 65 which is directed across the edge of the paper 24 and onto a photocell 66. The photocell 66 is connected to a suitable amplifier (not shown) which is operative to regulate valving which in turn controls the operation of the fluid actuator 62. If desired, additional ways may be provided for the support of the photocell 66. It is preferred that the bracket 67 which connects the photocell 66 with the arm 54 be provided with a means for adjusting the relative position of the photocell so that differences between various widths of paper and lengths of core may be accommodated. It is to be understood that the showing of the photocell type of control is illustrative and that other types of control mechanism may be utilized which will obtain a similar result. Further, it is to be understood that the sensing element, such as the photocell 66 may be seured to the rod 70 of the actuator 62, it then being necessary to provide for greater lateral adjustment thereof.

Where the rate of fluid flow to the actuator 41 is rather low, a rather slow rate of oscillation of the unwinding roll 20 is provided. There will always be some lag occurring through the stack so that the axial position along the lowermost stack roll will slightly lag the lateral position of the paper 24 at the unwinding mechanism. In certain instances, this lag will be so slight that it need not be compensated for. Under such circumstances, the arms 53 and 54 of the rewinding mechanism may be mechanically coupled to the unwinding mechanism for translation by the actuator 41.

It has been supposed that it would be impractical to oscillate the paper on the stack itself, both because of the difficulty in preventing wrinkles and so-called calender cuts resulting from wrinkles, and because oscillation would not effectively equalize wear. By way of illustration, it has been heretofore assumed that if a 40 inch width of paper was run on a supercalender stack having a useful width of 60 inches, and if the paper were oscillated for a distance of 20 inches, the wear in the central 20 inches of the useful face would continue to be more than that on the two outer 20 inch portions of the useful face. I have found, however, that when this is done the wear is substantially even over the entire 60 inches. In over six months of use of this invention, there has been no increase in the difference between the edges and the center of the calendered paper in gloss, finish, transparency, or density. Heretofore, there has been some difference between the edges and the center due to the manner in which the load is applied to the supercalender, and if oscillation caused uneven wear, it would be expected to increase this difference and produce a higher gloss finish, transparency, and density on the edges.

It has been found that wrinkling in the stack can be avoided during oscillation by using slow oscillating speeds, a higher rotational speed in the stack permitting

faster lateral or sideways oscillating movement. By way of example, no difficulty with wrinkling has been encountered with oscillating rates of 5 inches per minute at speeds of 500 feet per minute and faster.

It appears that the lack of increased difference between the center and edges of the paper with oscillation, as compared to the same paper calendered without oscillation, results from two principal factors. This may be explained by reference to Figure 5 which shows a view, exaggerated in the vertical direction, of what is believed to happen at a single nip between a pair of rolls. In the figure, the distance AD is the useful width of the nip and is the total distance engaged by the paper web 24 during oscillation between the rolls 11 and 12 of the calender stack. The distance AB indicates the zone of travel of one edge of the web 24, while the distance CD indicates the zone of travel of the other edge of the web 24. The paper is shown in the position defined by the limits B and D.

Between the points B and C, there is always paper between the two rolls of the nip. From B to A and from C to D there is paper between the rolls for a decreasing length of time, the time at any point depending on the characteristics of the oscillating motion. The type of oscillation does not appear to be important, as both harmonic and linear oscillation has been successfully used. Since in the ideal case the paper is uniformly compressible across its width, the pressure between the paper and the rolls near D is probably greater than between the paper and the rolls in the area between the points B and C, because in the oscillation cycle just completed, this portion of the rolls has not been exposed to the same amount of wear as has the portion between B and C. This higher pressure near D appears to cause faster wear of the soft rolls than occurs in the area BC.

Restated, it would appear that the rate of wear increases from B to A and from C to D about the same as the time of wear decreases, resulting in substantially equal wear from A to D.

Further, apparently the distance between the rolls at A is somewhat less than the distance between the rolls at B, as a result of normally equal loading of both journals of the top roll of the stack and the resistance to this load of the paper in the position BD. Therefore, the position of each roll, except the bottom roll in the stack, is the result of balance between the loading forces, which can be thought of as being applied at points A and D, and the resistance to compression offered by the paper.

Since the differences in roll diameters or position described are fairly small and incapable of measurement, I have been unable to determine which effect is responsible for the uniformity I have observed or whether both factors are involved and may vary in relative importance as operating conditions change.

While I have not observed that the characteristics of the oscillating motion are critical, and have used both harmonic and linear oscillation with equally good results, it is possible that with either particularly soft or abrasive papers a particular form of motion would prove advantageous.

For the purpose of minimizing roll defects by distributing the causes of ridges and corrugations over a wider area or width of the face of the roll, a total oscillation of from 1 to 3 inches is generally found satisfactory. For the purpose of equalizing wear and securing uniform results across the useful face of a supercalender stack, an oscillation of 20% or more of the paper width is satisfactory. It appears that the lower limit of effectiveness probably falls within the range between 10 and 20% of the paper width. For maximum effectiveness, the oscillation distance should equal the difference between the paper width and the useful width of the supercalender stack.

To secure the desired oscillation, obviously both the unwinding roll of paper and the winding roll of paper

must be moved more or less together. I prefer to provide a means for oscillating the unwinding roll parallel to its axis with a substantially linear motion as this is a most convenient method. I prefer also to move the winding roll parallel to its axis by means actuated by a photoelectric or other type of edge alignment device to which an identical motion is imparted so that the winding roll follows from side to side of the stack the position of the paper web, as it is delivered from the stack.

10 It is to be understood that in the case of either the winding mechanism or the unwinding mechanism, structure may be used which axially shifts the shaft and the roll together, or which axially shifts the roll and core with respect to the shaft. The choice is a matter of convenience and either type of shifting device may be used for either roll of paper. As explained above, it is also possible without departing from the spirit of this invention, to dispense with the edge alignment device and shift both rolls simultaneously or with a time delay or lag

20 between the motion of the unwind and winding rolls.

Although various minor modifications might be suggested by those versed in the art, it should be understood that I wish to embody within the scope of the patent warranted hereon all such embodiments as reasonably and 25 properly come within the scope of my contribution to the art.

I claim as my invention:

1. In a supercalendering machine having a stack of 30 rolls, means for unwinding a roll of paper to be treated by the rolls, and means for rewinding the treated paper, the improvement of means for continually axially oscillating the roll of paper, as it is being unwound, by an axial distance sufficient to produce thereby a lateral oscillation of the paper on the supercalender rolls.

35 2. In a supercalendering machine having a stack of rolls, means for unwinding a roll of paper to be treated by the rolls, and means for rewinding the treated paper, the improvement of means for continually laterally oscillating the paper unwinding means by an amount 40 needed to produce thereby a lateral oscillation of the paper on the supercalender rolls.

45 3. In a supercalendering machine having a stack of rolls, means for unwinding a roll of paper to be treated by the rolls, and means for rewinding the treated paper, the improvement of means acting on the roll of paper as it is 50 being unwound, to oscillate the portion of the paper being supercalendered laterally along the length of the supercalender rolls, and means synchronizing the lateral position of the rewind means with the lateral position of the paper being discharged from the stack.

55 4. In a method of operating a supercalender having a stack of rolls, means for unwinding a roll of paper to be treated by the rolls, and means for rewinding the treated paper, the improvement of continually slowly oscillating the roll of paper in an axial direction, as it is being unwound, by an axial distance sufficient to produce thereby a lateral oscillation of the paper on the supercalender rolls.

60 5. In a method of operating a supercalender having a stack of rolls, means for unwinding a roll of paper to be treated by the rolls, and means for rewinding the treated paper, the improvement of continually slowly oscillating the unwinding means in a direction parallel to the roll axes by an amount needed to produce thereby a lateral oscillation of the paper on the supercalender rolls.

65 6. In a method of operating a supercalender having a stack of rolls, means for unwinding a roll of paper to be treated by the rolls, and means for rewinding the treated paper, the improvement of continually slowly oscillating the roll of paper a selected distance in a direction parallel to its axis, as it is being unwound, to thereby oscillate the portion of the web of paper being supercalendered a selected distance along the length of the supercalender 70 rolls, and oscillating the rewind means in a similar direction.

tion in substantial synchronization with the position of the paper being discharged from the stack of rolls.

7. In a method of supercalendering a web of paper, the improvement of supercalendering a portion of the web and continually laterally oscillating said portion of the web while it is being supercalendered.

8. In a supercalendering machine having a stack of supercalender rolls, the improvement in combination therewith of means for continually laterally oscillating the portion of the web being supercalendered, along the length of the supercalender rolls.

9. In a method of supercalendering paper including the step of feeding a web of paper intermediate a stack of calender rolls, the improvement of applying a continually

oscillating lateral movement to the web prior to its engagement with the stack, said movement being of a magnitude sufficient to thereby gradually move the paper back and forth along the length of the calender rolls during the supercalendering of the paper.
